FOLDABLE EMERGENCY WARNING SIGNAL

Kenneth J. Crompton, Willowdale, Ontario, and Theodore Hochstatter, Etobicoke, Ontario, Canada, assignors to Dominion Auto Accessories Limited, Toronto, Ontario, Canada

Filed Jan. 17, 1975, Ser. No. 541,848

Term of patent 14 years

Int. Cl. D10—06

U.S. Cl. D10—111

FIG. 4

FIG. 2

FIG. 1 is a perspective view of a foldable emergency warning signal showing our new design.

FIG. 2 is a perspective view thereof in a folded condition.

FIG. 3 is an enlarged fragmentary perspective view showing the top latching mechanism in a detached condition.

FIG. 4 is a fragmentary side elevational view of the base in an unfolded condition.

The faceting indicating a reflective surface is partially shown in FIGS. 1, 2 and 3 for convenience of illustration, it being understood that the faceting is uniformly continuous over the areas indicated. The opposite face of the signal is identical to that of the face shown. The signal is fragmentarily shown in FIGS. 3 and 4 for convenience of illustration.

I claim:

An ornamental design for a foldable emergency warning signal, as shown and described.
